INDUSTRIAL GAUGING HEAD WITH TRAVERSING MOUNT FOR DETECTING MATERIAL PROPERTIES

Bernard C. Holben, Dublin, Ohio, assignor to Industrial Nucleonics Corporation, a corporation of Ohio

Application February 21, 1958, Serial No. 49,752

Term of patent 14 years

(Cl. D52—1)

Fig. 1

Fig. 2

Fig. 3

Fig. 1 is a perspective view of an industrial gauging head with traversing mount for detecting material properties, showing my new design.

Fig. 2 is a front elevation, and

Fig. 3 is a section on lines 3—3 of Fig. 2.

The dominant features of my design reside in the portions shown in full lines.

I claim:

The ornamental design for an industrial gauging head with traversing mount for detecting material properties, as shown and described.
